(57) CLAIM

The ornamental design for a light pole standard, as shown and described.

DESCRIPTION

FIG. 1 is a front perspective view of a light pole standard in accordance with my design;

FIG. 2 is a top plan view thereof;

FIG. 3 is a bottom plan view thereof;

FIG. 4 is a left side view thereof, the right side view being a mirror image thereof;

FIG. 5 is a front perspective view showing an alternate embodiment of the light pole standard, showing a light pole in broken lines; and,

FIG. 6 is a front perspective view thereof of the light pole standard of FIG. 1, showing a light pole in broken lines. The broken lines showing a light pole in FIGS. 5 and 6 are included for the purpose of illustrating environmental structure only and form no part of the claimed design.
